CLAIM

The ornamental design for a casserole or similar article, substantially as shown and described.

DESCRIPTION

FIG. 1 is a front elevational view of a casserole or similar article, showing my new design, the rear view being a mirror image thereof;

FIG. 2 is a side elevational view thereof, the opposite side being a mirror image thereof;

FIG. 3 is a bottom plan view of the lid of FIG. 1;

FIG. 4 is a top plan view thereof;

FIG. 5 is a bottom plan view of the casserole of FIG. 1;

FIG. 6 is a top plan view thereof with the lid removed; and

FIG. 7 is a front elevational view of the lid of FIG. 1, the rear view being a mirror image thereof.

The casserole and lid are shown separately in FIGS. 3-7, for clarity of illustration.
